UNITED STATES PATENT OFFICE.

LEONARD L. LESOINE, OF EAST STROUDSBURG, PENNSYLVANIA.

FIRE-DOOR PEDAL.

Application filed April 5, 1924. Serial No. 704,511.

To all whom it may concern:

Be it known that I, LEONARD L. LESOINE, a citizen of the United States, residing at East Stroudsburg, in the county of Monroe and State of Pennsylvania, have invented new and useful Improvements in Fire-Door Pedals, of which the following is a specification.

This invention relates to locomotive fire doors and more particularly to the operating pedals therefor.

The primary object of this invention resides in the provision of a pedal, for the fire doors of locomotives, which can be adjusted to meet the demands of firemen in performing their duties.

With the aforesaid and other objects in view, this invention resides in certain novel features of construction, arrangement and combination of elements to be hereinafter set forth in the specification, illustrated in the accompanying drawings and pointed out in the appended claims, it being understood that the right is reserved to resort to such departures from the present disclosure as come within the scope of the claims.

In the accompanying drawings, forming a part of this application:

Fig. 1 is a rear view of a portion of a conventional type of locomotive boiler showing the elements of this invention applied in operative relation with the fire door thereof.

Fig. 2 is a side view thereof.

Fig. 3 is a plan view of the pedal and associated parts.

Fig. 4 is a detail perspective of the pedal per se.

Fig. 5 is a similar view of the pedal bracket per se.

Fig. 6 illustrates a modified form of pedal, the view being a perspective thereof.

Fig. 7 is a perspective view of a modified form of bracket, the same shown to provide an aperture instead of a slot.

Fig. 8 is a side view of a modified form of bracket.

Fig. 9 is a detail perspective view of a portion of the bracket shown in Fig. 8.

In the present illustration of this invention, a conventional type of locomotive fire door is shown at A and, while the same is of the steam actuated type, it is important to state that the elements of this invention can readily be associated with any type of loco-

motive fire door and operated with equal success and convenience.

Pivoted as at 5 to the frame of the fire door A is a bracket 6 preferably having a laterally extending slot 7 adjacent its outer end and an aperture 8 at the other end thereof.

Journaled in the aperture 8 of the bracket 6 is a bolt 9 which is adapted to pivotally support the inner end of a lever 10. This lever is coupled adjacent its medial point to the bracket 6 by a threaded bolt 11 which passes through the slot 7 in the bracket and is retained in association therewith through the instrumentality of a threaded collar 12 preferably having a handle thereon. The lever 10 is provided with a series of spaced apertures 13 which are adapted to accommodate a lug 14 formed on a pedal 15 having a hook 16 disposed on one edge thereof to overhang the lever for assisting the lug 14 in maintaining a rigid connection between the lever and pedal. Should it be found necessary to utilize additional hooks such as 16 they can be formed to lie on opposite sides of the lug 14 so as to engage opposite edges of the lever as shown in Fig. 6.

With this structure associated with a fire door of a locomotive the bracket 6 is pivoted so one end thereof will operate in the region of the fire door latch manipulating mechanism and, through the instrumentality of the bolts 9 and 11 associated with the bracket, the lever 10 is not only susceptible of vertical adjustment relative to the bracket but it can be swung either to the right or left of the same without interfering with the operation of the adjusting element therefor. In the utilization of the particular pedal with the lever variable leverage can be obtained on one side of the pivot 5 especially for the reason the pedal can be readily disengaged from the lever to shorten or lengthen the same.

In the modified form shown in Figs. 8 and 9, a bracket 6' is shown, the same having a depending arm 7^a provided with a series of apertures 7^b arranged to receive a pin 8^a adapted to retain the lever 10 in any desired vertical position so as to rock the bracket through the instrumentality of the pedal 15.

With this invention fully set forth, it is manifest that means are provided to readily

operate the fire door manipulating mechanism of locomotives and, through the simplicity of the assemblage disclosed, the same can be manufactured and installed at the minimum cost.

Having thus described my invention, what I claim and desire to protect by Letters Patent is:

1. A fire door pedal of the character set forth comprising a pivoted bracket having a laterally extending slot therein, a lever swivelly connected to the bracket, an adjusting bolt carried by the lever with its free

end extending through the slot of the bracket, a threaded collar on the free end of the bolt, and a pedal extensibly connected to the lever.

2. A fire door pedal of the character set forth comprising a pivoted bracket, a lever swivelly connected to the bracket, an adjusting bolt carried by the lever with its free end extending through the bracket, a threaded collar on the bolt, and a pedal extensibly connected to the lever.

In testimony whereof I affix my signature:

LEONARD L. LESOINE.
